LAWRENCE B. SPERRY, OF BROOKLYN, NEW YORK, ASSIGNOR TO THE SPERRY GYROSCOPE COMPANY, OF BROOKLYN, NEW YORK, A CORPORATION OF NEW YORK.

MECHANICAL PILOT FOR AEROPLANES.

1,324,134.

Specification of Letters Patent.

Patented Dec. 9, 1919.

Application filed April 24, 1916. Serial No. 93,078.

To all whom it may concern:

Be it known that I, LAWRENCE B. SPERRY, a citizen of the United States, residing at 1505 Albemarle road, borough of Brooklyn, New York city, in the county of Kings and State of New York, have invented certain new and useful Improvements in Mechanical Pilots for Aeroplanes, of which the following is a specification.

10 This invention relates to the automatic control of aeroplanes. Its main object is to improve upon and simplify the present types of the so-called automatic stabilizers, by eliminating all auxiliary control handles. 15 In the system of control as outlined in the copending application of Elmer A. Sperry, Serial No. 851,477, filed July 17th, 1914, the pilot is enabled to control the machine at will while it is under the control of the gyroscope by means of an auxiliary handle or handles which shift the relative position of the contacts on the gyroscope and on the aeroplane. By my invention, I provide means whereby the aeroplane may be controlled at will under similar circumstances by means of the usual control handles, so that the aviator makes the same motions whether the machine is under automatic or manual control. Another object is to devise 30 a reliable means for preventing the stalling of the aeroplane by automatically volplaning it when it falls below its critical speed.

Referring to drawings in which what I now consider the preferred forms of my invention are shown: Figure 1 is a diagrammatic development of one of my systems of control. Fig. 2 is a plan view of a portion of a servo motor, parts being broken away to show the details thereof. Fig. 3 is a section on line 40 3, 3, Fig. 2. Fig. 4 is an end elevation of the servo motor partly in section. Figs. 5 and 5^A are details of Fig. 4. Fig. 6 is a diagrammatic development of a modified system of control. Fig. 7 is a section of a 45 constructional detail of the gyroscopic unit used in this system. Fig. 8 is an end elevation thereof. Fig. 9 is a detail being a section on line 9, 9 of Fig. 7. Fig. 10 is a detail.

50 In the diagrammatic outlay in Fig. 1, the master governor for controlling the stability of the aeroplane is shown at 1, and consists in this instance of a gyroscope 2 mounted on a vertical spinning axis within the usual

gimbal rings 3. Contacts for controlling the 55 servo motor 4 are arranged about each axis. Said contacts are shown as consisting of a pair of segmental contact strips 5, 6 mounted on or connected to one of gimbal rings 3, and a brush 7 on a relatively fixed portion 60 of the aeroplane. Preferably the brush is pivotally mounted on bracket 8 so that a follow-up movement may be communicated thereto by means of a wire 9. The above details form no part of the present invention, 65 however, but are set forth in detail in the aforesaid application of Elmer A Sperry and in my copending application Serial No. 87,434 for automatic pilots for aeroplanes, filed March 29th, 1916. 70

The usual manual means for controlling the elevating rudder 10 is represented at 11, while the corresponding elements for the lateral control are shown at 12, 13. Flexible members or wires connect the handle 11, 75 rudder 10 and the servo motor 4, while this system is connected through follow-up wire 9 to the governor 1. According to this invention means are provided to temporarily sever the above connections at some point so 80 as to allow the relation between the governor and the rudder to be changed. The change is effected by means of the handle 11. The severance of the said connections may also, if desired, be accomplished through the 85 same handle 11. For this purpose, I locate in the said connections a lost motion device 100 comprising a pair of drums 14 and 15.

The drum 14 is directly connected to handle 11 through wires 16. Drum 15 is 90 connected to drum 14 only by means of a lost motion device which will permit a limited relative movement of drum 14, which motion is opposed between said limits by a resilient or yielding means. This connection may consist of a pin 17 secured to drum 15 and projecting through a curved slot 18 in drum 14. The pin 17 is connected to drum 14 through a spring 19 adapted normally to maintain the pin in the center of 95 the slot. The slight lost motion which takes place when the aviator pushes on handle 11 is made use of to bring into action electro-magnetic means hereinafter described for temporarily disconnecting the servo motor 4 100 and the control rudder 10.

For this purpose contacts 20, 21 are located upon drum 14 with which contact 22

projecting from drum 15 is adapted to coöperate. No attempt is made in this application to show the preferred form of the mechanical details of the lost motion device, 5 as this device is shown completely in my aforesaid copending application.

The servo motor 4 consists essentially of a continuously rotating shaft 50 driven preferably by means of a wind motor 51; 10 and a plurality of windings 52, 53, 54, and 55, adapted to actuate clutches thereby connecting the proper control rudder with the wind motor for actuating the same. As shown, the shaft 50 drives two intermeshing 15 pinions 26, 27 in opposite directions (Figs. 2 and 3). Pinion 27 drive gears 30 and 31 while pinion 26 drives gears 32 and 33, so that the gears 30, 32 and 31, 33 will be rotated in opposite directions. The winding 20 52 is adapted to throw the clutch disk 35 and the clutch face of gear 30 into engagement by attracting armature 101 so that the shaft 36 on which disk 35 is mounted will be driven in the same direction as gear 30, 25 while winding 53 is adapted to throw gear 32 and said disk into engagement whereby said shaft will be rotated in an opposite direction. The said windings 52, 53 are in circuit with the contacts 5, 6 on the gyroscopic 30 governor, while windings 54, 55 are in circuit with contacts 56 on the other axis of the gyroscope, so that whenever the aeroplane tilts the circuit is completed to cause the servo motor to right the same.

35 Limiting means are preferably provided for the servo motor. For this purpose gear 37, which is driven from shaft 36, may be provided with a spiral slot 38 which is adapted to move the lever 39 to make and break contacts 40, 41 when the limit of motion of the control rudder is reached. The means for disconnecting the control rudder from the master governor is represented in this figure by gear clutch 42 which is shown 40 in the form of a gear 43 adapted to mesh with the gear 44 driven by said gear 37. The preferred mechanical construction for these parts is shown in Figs. 2 and 4, hereinafter described. A pivoted arm 42 serves to support gear 43 while the spring 46 normally holds gears 43, 44 in mesh. An electromagnet 47 is adapted, upon being excited, to throw out said gears. Said magnet is in circuit with said contacts 20, 21, 22 on the 45 lost motion device above described, so that as soon as the aviator pushes upon the handle 11, gears 43, 44 will be disconnected. In this form of the invention also, the follow-up wires 9 leading to the brushes on the 50 master governor from the servo motor are connected to the shaft 36 by means of a drum 45 or to some other portion of the servo motor which remains permanently coupled to the system.

55 The lost motion device may also be made

use of to control the servo motor in place of the contacts on the gyroscope, if the aviator should desire to cut out the automatic control. For this purpose, switches 60, 61 are provided. Each switch, when the blades engage contacts 62 completes the circuits already described, but when thrown into the position shown the contacts on the gyroscope will be cut out, and at the same time the contact points 20, 21 will be separately connected to coils 52, 53 respectively. 70 75

The preferred construction of servo motor is shown in Figs. 2 and 4, the parts being numbered to correspond to Fig. 1. Since the two sides of the motor are duplicates they 80 will be described together. Pinions 62 are mounted on shafts 36, which, it will be remembered carry clutch disks 35. Arms 63 are pivoted about axes 64 in line with shafts 36 and carry gears 65 which mesh with pinions 62 and other pinions 66 adapted to be thrown into and out of mesh with large gears 67 by the oscillation of arms 63. The drums 68 by which the servo motor is connected through wires 70 to the rudder are 85 mounted on gears 67. The position of arms 63 is controlled by means of links 71, which are raised and lowered by the revolution of cams 72, 72' (Figs. 5 and 5^A) one of which is secured to the shaft 73 carrying crank 74, 90 while the other is secured to the sleeve 173 forming the hub of crank 74'. Springs 75 normally hold the rollers 76 on links 71 in engagement with the cams while other springs 77 normally hold the cams in such 100 position that gears 66 and 67 are in mesh. Solenoids 78 corresponding to electromagnets 47 serve to rotate the cams through rocker arms 74, when excited, so that the gears 66 and 67 are disconnected upon the 105 initial movement of handles 11 or 13. Further movement of either handle will serve to shift the relation of the governor and the control planes to the desired extent. When the handle is released, the governor 11 again assumes control and maintains the machine in the position for which it is set.

The servo motor is also preferably equipped with brakes 80 adapted to prevent the pressure of the air puffs on the control 115 planes or rudders from reaching back into the follow-up system and governor. The brakes are normally retracted by springs 81, but will be applied upon the excitation of the electro-magnets 82. The brake shoe is 120 shown as acting directly on clutch disk 35. I find it desirable to so construct each brake that it is held out of engagement with said disk not only when either one or the other of coils 52, 53 are excited, but also when the 125 entire electrical system is thrown out and the aeroplane controlled by hand. This last feature is rendered necessary by the fact that the servo motor is so connected in the control system that the parts are revolved 130

by the movements of the aviator when the electrical system is thrown out as well as by the automatic control. For this purpose magnets 82 are provided with two differential windings 83, 84 (Fig. 1) the former being in circuit with windings 52, 53 while the latter is connected to the main supply. It will thus be seen that the brake will be applied only when the main supply is on and 10 the clutch windings are not excited, which is the condition desired, but that as soon as either of the said windings is excited, the two windings 83, 84 will neutralize each other and release the brake. A generator 15 150 of any suitable form may be used to supply current for the system. A switch 151 is shown in circuit with the generator so that the entire electrical system may be de-energized and the planes moved directly by 20 hand, if desired.

Figs. 6 to 9 illustrate important modifications in the method of altering the relation between the master governor and the stabilizing vanes or rudders. In the form shown 25 in Fig. 1, the servo motor and the governor are permanently connected through follow-up wires 9, and the connection between the servo motor and the rudders is broken to permit the said alteration. In Figs. 6 to 9 30 on the other hand the servo motor and rudders are permanently coupled, while a throwout device is placed in the follow-up connections between the servo motor and the governor.

35 This device is preferably located adjacent the gyroscopic unit, as shown in Figs. 7 and 8, wherein 3' represents a gimbal ring and 5', 6' the reversing contacts mounted thereon. The brush 7' is mounted on a member 40 90 loosely mounted on shaft 91. Pivoted at 92 on one face of member 90 is a U shaped spring 93, the free ends of which are normally pressed toward said member by a spring 94. An electro-magnetic clutch face 45 95 is secured on shaft 91 against axial movement adjacent member 90, so that, upon excitation of the winding 96 member 90 will be drawn toward magnet 95. A plurality of pins 97 project from a plate 98 through 50 holes in member 90 and bear against the hub of clutch magnet 95. Plate 98 is provided with flanges 98' adapted to bear against the two legs of the spring. It will thus be seen that the excitation of winding 96 will not 55 only couple members 90 and 95 together, but will move the free ends of spring 93 away from both members, since the points of contact between the spring and plate 98 will remain stationary, and pivot 92 will move 60 with member 90. Projecting from the support 99 of contact segments 5', 6' is a T shaped plate 105. When the clutch is released the plate is positioned as shown in Fig. 9, the plate fitting snugly between the 65 ends of spring 93, but when the clutch parts

are in engagement the ends are thrown back so that a limited play is allowed between the stem of plate 105 and the spring. A plate 106 about the width of the broadest portion of plate 105 holds the two legs apart. The 70 follow-up wire 9' from the servo motor is shown as secured to an arm 107 pivoted at 108 on a bracket 109 extending from support 1'. Instead of using a return wire a spring 110 may be employed to move the arm in one 75 direction. The arm is connected to member 95 by means of a bolt 111 adjustably secured in a slot 112, which extends through a similar slot in an extension 113 of member 95.

According to this modification, the winding 96 is normally energized and the two members 90 and 95 locked together. To accomplish this purpose, a relay 114 may be interposed between switch 60' and the winding, so that the closing of either of contacts 80 20 or 21 will break the circuit through the winding at 115. This will release member 90 which will be moved back under the influence of spring 94 acting against plate 98 through spring 93 and will also straighten 90 up the spring. The purpose of spring 93 and its associated parts is to centralize brush 7' with respect to contacts 5', 6'. When the clutch is engaged, the brush moves, of course with member 95, and should have no connection with the sensitive gyroscope, but when the clutch is released, preparatory to resetting the members, I find it desirable that the brush be brought to the neutral position between the contacts. The spring 93 100 automatically accomplishes both of these results, since the ends closely engage the T end of plate 105, when the clutch is released, while when it is closed the spring is moved away from said end, as explained. 105

I find it desirable not only to provide means for manually shifting the relation between the governor and rudders, but also to provide an automatic means for effecting this purpose under special conditions. 110 More specifically I provide an automatic volplane attachment, which, when the velocity of the machine falls below the critical speed, automatically volplanes the aeroplane. As explained in my aforesaid application, an auxiliary brush 120 is provided about the lateral axis of the gyroscope, which is placed at the desired angle to the main brush 7, and to which connections are made when brush 7 is cut out. The means for 115 altering these connections are quite different from my said other application however. According to this invention I make use of the fact that, when an aeroplane falls below its critical speed, not only does its velocity 120 through the air become less than a predetermined amount, but also its angle of incidence becomes greater than a given value. I employ the latter feature according to this invention by pivoting on the aeroplane an 125 130

approximately horizontal vane 121, adapted to point in the direction in a vertical plane in which the air strikes the aeroplane. Springs 122 may be used to maintain the 5 vane at the normal angle of attack if desired. But as soon as the aeroplane falls below its critical speed, the aeroplane begins to fall causing the plane to tilt in a counter-clockwise direction. A contact 123 is completed thereby which energizes a coil 124, operating thereby a relay 125 which throws brush 7 out of circuit and brush 120 in circuit. This means for volplaning the 10 machine possesses quite an advantage over a velocity controlled device, since the critical speed of an aeroplane is not a constant quantity, but varies with the load it is carrying at the time, while the critical angle of attack is a constant for each aeroplane, irrespective of the load it is carrying, so that 15 the control vane need never be adjusted after it is once set.

In operating an aeroplane constructed in accordance with my invention, the aviator 20 uses the usual control handles or foot pedals in the same manner, irrespective of the position of switches 60, 61. If the switches are in the position shown, the control planes will be operated directly from contacts 20, 25 21, 20', 21' through the servo-motor, while if the switches are thrown into contact with points 62, the planes will be operated from the contacts 5, 6 and 56 on the master governor, the positions of which are under the 30 supervision of the aviator by simply pushing on the levers 11, 13. This movement severs the connections between the master governor and the control rudders at some point, such as between the servo-motor and 35 the rudders through clutch gears 43, 44 or between the servo-motor and the governor through clutch 90, 95. At the same time the said movement moves the rudders directly to the desired position, where the lever is 40 released, allowing the governor to take up the control in the new position. If at any time the limiting value of the angle of attack is exceeded, the vane 121 will automatically volplane the machine. When the 45 switches are in contact with neither set of contacts and the generator circuit is open, the aviator controls the planes directly.

Having described my invention, what I claim and desire to secure by Letters Patent is:

1. In an automatic pilot for aeroplanes, the combination with a master governor, of a servo-motor controlled thereby, a control rudder, a manual control lever, means interconnecting the parts already named, said means including a follow-up connection between said governor and rudder, and a device adapted to disconnect at will the follow-up connection between the control rudder and the governor, whereby said lever

may be used for shifting the relation between said rudder and said governor while said parts are disconnected.

2. In an automatic pilot for aeroplanes, the combination with a master governor, of a servo-motor controlled thereby, a control rudder, a manual control lever, means interconnecting the parts already named including a follow-up connection between said governor and rudder and a device operated by said lever adapted to disconnect the follow-up connection between the control rudder and governor and to permit said lever to shift the relation between said rudder and said governor.

3. In an automatic pilot for aeroplanes, the combination with the manual control lever and control rudder, of a master governor, a servo-motor controlled therefrom, a lost motion device located in the connections between said lever and said rudder, a follow-up connection between said rudder and governor, and means brought into action by said lost motion for disconnecting the follow-up connection between the rudder and the governor.

4. In an automatic pilot for aeroplanes, a servo-motor, a master governor, a follow-up connection between said motor and governor, a control rudder connected with the servo-motor, means for preventing air pressure on the rudder from reaching the governor, and means for manually operating said rudder, said first mentioned means being controlled by said last named means.

5. In an automatic pilot for aeroplanes, a servo-motor, a master governor, a follow-up connection between said motor and governor, a control rudder connected with the servo-motor and a brake responsive to the deenergizing of the servo-motor for preventing the air pressure on the rudder from reaching the governor.

6. In an electrically controlled automatic pilot for aeroplanes, a servo-motor, a master governor, a follow-up connection between said motor and governor, a control rudder connected with the servo-motor, a brake on the servo-motor and means adapted to apply the brake only when the servo-motor is deenergized and at the same time the electrical system is operative.

7. In an automatic pilot for aeroplanes, the combination with a pendulous device, of contacts on said device and on an adjacent contact carrying part of the aeroplane, a servo-motor controlled therefrom, a follow-up connection from the servo-motor to a member positioned adjacent said part, and means for coupling and uncoupling said part and said member.

8. In an automatic pilot for aeroplanes, the combination with a pendulous device, of contacts on said device and on an adjacent part of the aeroplane, a servo-motor

controlled therefrom, a follow-up connection from the servo-motor to a member positioned adjacent said part, means for coupling and uncoupling said part and said member, and means for shifting the relative positions of said part and said member when so uncoupled.

9. In an automatic pilot for aeroplanes, the combination with a pendulous device and a manual control handle, of contacts on said device and on an adjacent part of the aeroplane, a servo-motor controlled therefrom, a follow-up connection from the servo-motor to a member positioned adjacent said part, and means for coupling and uncoupling said part and said member, whereby the relative positions of said part and member may be shifted by means of said handle.

10. In an automatic pilot for aeroplanes, the combination with a pendulous device and a manual control handle, of contacts on said device and on an adjacent part of the aeroplane, a servo-motor controlled therefrom, a follow-up connection from the servo-motor to a member positioned adjacent said part, a rudder, connections between said rudder and handle, a lost motion device in the connections between the handle and the rudder, and means responsive to an initial movement of said device for uncoupling said part and said member.

11. The combination with a gyroscope mounted for turning about an axis, a member mounted for movement about the same axis, a plurality of electric contacts mounted on said gyroscope and on said member, said contacts comprising a plurality of separated contact segments and a coöperating brush, a clutch member adapted to engage and disengage said member, means for oscillating said clutch member, and resilient means for restoring the said contacts to their neutral relation when said clutch is released.

12. The combination with a gyroscope mounted for turning about an axis, a member mounted for movement about the same axis, a plurality of electric contacts mounted on said gyroscope and on said member, said contacts comprising a plurality of separated contact segments and a coöperating brush, a clutch member adapted to engage and disengage said member, means for oscillating said clutch member, resilient means for restoring the said contacts to their neutral relation when said clutch is released and means releasing the connection between said resilient means and the gyroscope when the clutch is engaged.

13. In an aeroplane the combination with an elevating plane of a pendulous device, a servo-motor connected with said plane, means actuated by said device for controlling said motor, a movable horizontal vane adapted to be turned in the direction of the

angle of attack, and means including an electrical translating device responsive to the turning through a predetermined angle for altering the relation between said means and said device, whereby the machine is automatically volplaned.

14. The combination with an aeroplane having a manual control lever, a control rudder, a servo-motor and a pendulous device for normally controlling the servo-motor, of contacts connected with said control lever, and means for controlling from said contacts either the servo-motor directly, or for permitting shifting the effective relation between the pendulous device and the rudder.

15. In an aeroplane, the combination with the usual manual control devices and stabilizing planes, of an electro-magnetic servo-motor, a gyroscopic pendulum, contacts controlled by said pendulum for governing said servo-motor, a second set of contacts operated by said manual devices for governing said servo-motor, means for rendering either one or the other of said sets operative to perform the said functions, and means for adjusting the relation between the pendulum contacts and the said planes, including said manual devices and the contacts operated thereby.

16. In an aeroplane, the combination with the usual manual control devices and stabilizing planes, of an electro-magnetic servo-motor, a gyroscopic pendulum, contacts controlled by said pendulum for governing said servo-motor, a second set of contacts operated by said manual devices for governing said servo-motor, means for rendering either one or the other of said sets operative to perform the said functions, means for adjusting the relation between the pendulum contacts and the said planes, including means controlled by said contacts for severing the connection between the pendulum contacts and the stabilizing planes.

17. In an automatic pilot for aeroplanes, the combination with a master governor, of a servo-motor controlled thereby, a control rudder connected to said motor, a follow-up connection between said rudder and governor and means for disconnecting said follow-up connection at will.

18. In an automatic pilot for aeroplanes, a control rudder, a manual control lever and a governor connected thereto, a servo-motor controlled by said governor, a follow-up connection between said rudder and governor and means brought into action by movement of said control lever for disconnecting said follow-up connection.

19. In an aeroplane, in combination, an elevating plane, a pendulous device, a servo-motor connected with said plane, means actuated by said device for controlling said motor, a movable, normally horizontal vane adapted to be turned in the direction of the

- angle of attack, a circuit controller actuated by said vane and means controlled by said circuit controller for altering the relation between said first named means and said device.
20. In an aeroplane, in combination, a pendulous device, a plurality of electrical contacts controlled by said device, a normally horizontal vane, a plurality of electrically controlled contacts, a conductor connecting each of said first mentioned contacts to a corresponding one of the other contacts, and means including said first named contacts for controlling the equilibrium of the aeroplane.
21. In an automatic pilot for aeroplanes, the combination with the manual control lever and control rudder, of a master governor, a servo-motor controlled therefrom, a follow-up connection between said rudder and governor, means brought into action by operation of said lever for disconnecting the follow-up connection between the rudder and the governor and means for controlling said servo-motor directly from said lever.
22. In an aeroplane, in combination, a stabilizing plane, a manually operated lever for operating the same, a servo-motor, a pendulum, contacts controlled by said pendulum for governing said servo-motor, a second set of contacts operated by said lever, connections between said second set of contacts and said servo-motor, a switch for rendering said first-named contacts ineffective to control said servo-motor, a follow-up connection between the plane and said first-named contacts, means for disconnecting said follow-up connection and electrical connections between said second set of contacts and said last named means.
23. In an aeroplane, in combination, a stabilizing plane, a pendulum, contacts controlled by said pendulum, a servo-motor, a follow-up connection between said stabilizing plane and said contacts, electrically operated means for connecting and disconnecting said follow-up connection, a manually operated lever, electrical connections between certain of said contacts and said servo-motor, contacts controlled by said lever, electrical connections between certain of said last mentioned contacts and said servo-motor and means for controlling said electrically operated means from said lever.
24. The combination with an aeroplane having a manual control lever, a control rudder, a servo-motor and a pendulous device for normally controlling the servo-motor, of contacts connected with said control lever, means including said contacts for controlling the servo-motor from said lever, and means, also including said contacts, for shifting the effective relation between the pendulous device and rudder by movement of said lever.
25. In an aeroplane, a rudder, a master governor for controlling said rudder, said master governor being in turn controlled by said rudder, a manually operated device, means rendered operative by movement of said device for removing said master governor from the control of said rudder and means for changing the effective relation between said master governor and rudder upon further movement of said device.
26. In a dirigible device, the combination with a rudder, of an automatic control device therefor, a manual control device therefor, and means brought into action by the initial actuation of said manual device for rendering inoperative said automatic device.
27. In a dirigible device, the combination with a rudder, of an automatic control device therefor, a manual control device therefor, and means brought into action by the initial actuation of said manual device for rendering inoperative said automatic device and by continued movement thereof for actuating said rudder from said manual device.
28. The combination with a gyroscope, of a control member connected thereto, an independently mounted co-operating control member, releasable means for turning said second member, and yielding means for normally restoring said second member to a predetermined position.
29. The combination with a gyroscope, of a control member connected thereto, an independently mounted co-operating control member, releasable means for a rudder controlled by the relative movement of said members, a follow-up connection between the rudder and the second member, a releasable means in said connections for disconnecting said connection from the member, and means for restoring said member to a predetermined position.
- In testimony whereof I have affixed my signature.

LAWRENCE B. SPERRY.
